[57] CLAIM

The ornamental design for a police baton, as shown and described.

DESCRIPTION

FIG. 1 is a front elevational view of a police baton showing my new design. A rear elevational view would be the same in appearance;

FIG. 2 is a top plan view of my police baton;

FIG. 3 is a bottom plan view of my police baton;

FIG. 4 is an end view of my police baton taken from the left end of FIG. 1; and

FIG. 5 is an end view of my police baton taken from the right end of FIG. 1.
